UNITED STATES PATENT OFFICE.

EDWIN CLAY, OF WADSWORTH, NEVADA.

STEAM-BOILER CROWN-BAR.

SPECIFICATION forming part of Letters Patent No. 663,064, dated December 4, 1900.

Application filed September 12, 1900. Serial No. 29,755. (No model.)

To all whom it may concern.

Be it known that I, EDWIN CLAY, a citizen of the United States, residing at Wadsworth, county of Washoe, State of Nevada, have 5 invented an Improvement in Steam-Boiler Crown-Bars; and I hereby declare the following to be a full, clear, and exact description of the same.

My invention relates to devices for bracing 10 and supporting the crown-sheet of steam-boiler furnaces.

It consists of bars formed with parallel sides and transverse connecting members adapted to receive the stay-bolts which pass 15 through the crown-sheet and into said cross members. The bars thus constructed have flanges or plates formed upon their ends, with curvatures which fit and are bolted to the shell of that portion of the boiler above the 20 crown-sheet and technically termed the "wagon-top."

My invention also comprises details of construction which will be more fully explained by reference to the accompanying drawings, 25 in which—

Figure 1 is a vertical section through the bar and connections. Fig. 2 is a view of the same.

It has been customary in this class of structures to extend the "crown-bars," so called, 30 above the crown-sheet, and the ends are formed with toes, which are secured to the upper edges of the inner sheets of the water-leg. Washers are fitted between the crown-bar and the top of the sheet, and bolts pass 35 through the bar, the washers, and the sheet, and thus support and stay the latter against the internal pressure of the steam. This construction is objectionable, first, because at 40 the fastening-points and under the washers the water is kept away from the sheets and the latter are liable to be burned out by the heat from the opposite side, and, secondly, it is necessary to remove parts of the superstructure 45 of the boiler to enable a workman to get into the interior for the purpose of repairs when necessary. My invention is designed to overcome these defects and to provide a superior stay for the crown-sheet.

50 In the drawings I have illustrated a sufficient portion of that part of the boiler which

is situated above the crown-sheet to show the application of my invention.

A is the curved shell or wagon-top of the boiler, which extends down upon each side 55 and connects with the outer shell of the water-legs 2.

3 is the crown-sheet, which extends across above the fire-box 4 of the furnace, and the edges of the crown-sheet are flanged and riveted to the inner sheets 5 of the water-legs, 60 as shown.

The crown-bar is made of cast-steel or other suitable material and consists of the side plates 6 and the transverse connecting-ribs 7. 65

The ends of the crown-bar are formed with curved plates or flanges 8, which extend sufficiently above and below the bar and have holes made through them to receive the rivets 9, by which they are secured to the outer 70 shell A, so that the crown-bars extend across the interior of the boiler above the crown-sheet 3.

Each pair of the transverse ribs 7 of the crown-bar has a bottom plate 10 of sufficient 75 thickness, and through this is made a screw-threaded hole of sufficient diameter to receive the correspondingly-threaded end of the stay-bolt 11. These bolts may be formed with heads upon them, as shown at 12, and 80 the hole in the crown-sheet being made vertically in line with the holes in the crown-bars the bolts can be inserted from within the fire-box and screwed up into the crown-bar, so as to form a complete support and stay for 85 the crown-sheet.

It will be understood that there are as many crown-bars extending across above the crown-sheet as the length of the fire-box makes necessary, the distance between the 90 centers of the bolts being such that the crown-sheet will have an ample support therefrom, and if desired the bolts may be screwed into the ribs 7 of the crown-bar, and the lower ends may also be threaded to receive nuts, as 95 at 12^a, which are screwed onto the lower ends of the bolts and against the bottom of the crown-sheet 3. By this construction there is a free space around the stay-bolts 11, so that the water has access to the inner surface of 100 the crown-sheet, and the sheet is thus rendered more durable and resistant against the

action of the heat upon the opposite side. The crown-bars being supported from and secured to the outer shell do not contact with any part which is subjected to the direct action of the fire. The stay rods or links 13 are connected with the top of the boiler-shell by lugs 14 and are here shown in pairs extending down to near the crown-bar, with which they are connected by a loose intermediate link 15, which allows for any necessary adjustment in making the connection or which may be caused by expansion and contraction of the parts. Crown-bars made in this manner not only serve to sustain the crown-sheet, but also form the transverse stays between the sides of the boiler, and thus obviate the necessity for stay-rods between the crown-bars.

Having thus described my invention, what I claim as new, and desire to secure by Letters Patent, is—

1. A crown-bar for boilers consisting of a single integral structure including parallel side plates, and transverse connecting members adapted to receive the crown-sheet stay-bolts, said plates having the ends formed to fit the interior of the boiler-shell, and rivets by which the bars are secured thereto.
2. Crown-bars for boilers consisting of parallel plates in planes at right angles of the crown-sheet having flanged ends by which they are secured to the interior of the boiler-shell, transverse ribs integral with the plates and connecting said bars having screw-threaded holes in the bottom and stay-bolts passing through corresponding holes in the

crown-sheet and into said holes in the crown-bars.

3. Crown-bars for boilers consisting of a single integral structure including parallel plates with transverse connecting-ribs adapted to receive the crown-sheet stay-bolts and end extensions fitting the interior of the boiler-shell, all parts being integral of cast-steel.

4. Crown-bars for boilers, consisting of parallel vertically-disposed plates with integral transverse connecting-ribs and end plates fitting and adapted to be secured to the exterior shell of the boiler above the crown-sheet, stay-rods pivotally secured at both ends and connecting the arch of the boiler with the crown-bars intermediate of their length, and bolts passing through the crown-sheet and into the transverse ribs of the crown-bars.

5. As an article of manufacture, combined crown-bars consisting of separated plates formed with integral transverse stays substantially as herein described.

6. Crown-bars for boilers consisting of a single integral structure including parallel plates vertical edgewise, and intermediate connecting-ribs in pairs with bottoms perforated for stay-bolts.

In witness whereof I have hereunto set my hand.

EDWIN CLAY.
